CLAIM

The ornamental design for a combined door stop and clothing stand, as shown and described.

DESCRIPTION

FIG. 1 is a perspective view of a combined door stop and clothing stand showing my new design. The broken lines showing a partial view of a door are for illustrative purposes only and are not part of the claimed design; FIG. 2 is a left side view. The right side being a mirror image thereof. The broken lines showing a view of a hat are for illustrative purposes only and are not part of the claimed design;

FIG. 3 is a front view;

FIG. 4 is a rear view;

FIG. 5 is a top view; and,

FIG. 6 is a bottom view.

FIG. 1

FIG. 5**FIG. 3****FIG. 6****FIG. 2****FIG. 4**
